ROSS T. ADAMS, OF BATTLE CREEK, MICHIGAN, ASSIGNOR TO KELLOGG COMPANY, OF BATTLE CREEK, MICHIGAN, A CORPORATION OF DELAWARE

CONTAINER FOR SHREDDED WHEAT BISCUIT AND THE LIKE

Application filed February 3, 1932. Serial No. 590,569.

This invention relates to containers for shredded wheat biscuit and the like.

The object of the invention is to provide simple, durable and relatively inexpensive and thoroughly effective means for packing fragile or brittle biscuits and the like in such manner as to eliminate as far as possible their tendency to crumble or be broken during the processes of shipping and handling.

With the foregoing and other objects in view, which will appear as the description proceeds, the invention resides in the combination and arrangement of parts and in the details of construction hereinafter described and claimed, it being understood that changes and variations in the combination of parts and in the details of construction may be made within the scope of what is claimed, and as more particularly suggested and indicated by the variations between the different claims, without departing from the spirit of the invention.

In the accompanying drawing forming part of this specification:

Figure 1 is a view looking down into the carton, with the top thereof cut away except along one edge, the top flap being shown hanging down at an angle.

Figure 2 is a view of the container showing the biscuit and the corrugated means there between.

Figure 3 is a sectional view taken at a right angle to the view shown in Figure 2.

Figure 4 is a detailed view.

Like reference numerals indicate corresponding parts in the different figures of the drawing.

In the accompanying drawing, the numeral 1 indicates a pasteboard carton having at the top thereof side flaps 2, and 3, which are folded one above the other and pasted together, and end flaps 4 and 5 which are folded beneath the side flaps 2 and 3.

The shredded wheat biscuit or other material 6, is disposed within the carton 1 in successive layers as shown in Figures 2 and 3, each layer being separated from the next adjacent layer by means of cushion partitions 7, 8, 9 and 10. A top cushion 11 is em-

ployed, and a bottom board 12 which may be either cushioned or uncushioned as desired.

The cushion effect of the partitions is secured preferably by making each partition of a board 13 and of relatively yielding paper 14 formed into corrugations which are pasted or otherwise secured to the board 13.

As best shown in Figure 3, the corrugations 14 of the cushioned partitions preferably extend parallel with the shreds or filaments of the biscuit, so that all of the several layers of biscuit tend to be held as one unitary mass by the relative interlocking of the cushioned corrugations with the grooves between the shreds of the biscuit.

The improved container serves in an inexpensive and protective manner to prevent trituration or relative grinding of the biscuits upon each other. Moreover, the corrugations of the partition parts are at once sufficiently yielding and sufficiently unyielding to permit the biscuits to be packed closely enough in the box, and between its top and bottom covers, to minimize the tendency of the biscuits to move around and frictionally contact with each other and thus to wear down or break off fragments in the processes of packing, shipping and emptying the carton.

While I have shown the partitions 13 as having corrugated cushions on only one side, it will be seen from Figure 4, that I may cushion both sides of the partition and I may also have the corrugations running cross-wise to the shreds of the biscuit if desired.

What is claimed as new is:

1. A container for shredded wheat biscuit and the like, comprising a carton, shredded wheat biscuit or the like arranged in superposed layers therein, and cushioned partitions disposed and superposed in parallel relationship between said layers of biscuit, said partitions being sufficiently yielding and sufficiently unyielding to grip the biscuit disposed between the partitions and hold the same against relative displacement, the cushioned surfaces of said partitions being formed of corrugations extending in parallel relation to the shreds of the biscuit within said container.

2. A container for shredded wheat biscuit

- and the like, comprising a carton, shredded wheat biscuit or the like arranged in superposed layers therein, and cushioned partitions disposed and superposed in parallel relationship between said layers of biscuit, said partitions being sufficiently yielding and sufficiently unyielding to grip the biscuit disposed between the partitions and hold the same against relative displacement, the cushioned surfaces of said partitions being disposed on one side of each partition and formed of corrugations extending in parallel relation to the shreds of the biscuit within said container.
- 15 Signed at Battle Creek, in the county of Calhoun, and State of Michigan this 28 day of January A. D. 1932.

ROSS T. ADAMS.
